(57) **CLAIM**

The ornamental design for a salt and pepper mill, as shown and described.

DESCRIPTION

FIG. 1 is a top, front perspective view of a salt and pepper mill, showing my design;

FIG. 2 is a bottom, front perspective view thereof;

FIG. 3 is a front elevation view thereof, with the rear elevation view being a mirror image of the front elevation view;

FIG. 4 is a right elevation view thereof, with the left elevation view being a mirror image of the right elevation view;

FIG. 5 is a top elevation view thereof; and,

FIG. 6 is a bottom elevation view thereof.

The broken lines shown in the drawings depict portions of the salt and pepper mill that form no part of the claimed design.

1 Claim, 4 Drawing Sheets
